Term of patent 3½ years

(Cl. D14—3)

The rear, not shown, is substantially plain, and the undisclosed side is a mirror image of the side shown.

This application is a division of my earlier application, Serial No. D. 53,106, filed October 23, 1958, now abandoned.

I claim:

The ornamental design for a frame for a child's cart, as shown and described.
